TOY SPINNING TOP

Peter Balleis, 55 Hermann-Lons-Strasse,
Zirndorf, near Nurnberg, Germany

Filed Aug. 3, 1965, Ser. No. 86,411

Claims priority, application Germany Feb. 13, 1965

Term of patent 14 years

(Cl. D34—15)

The figure is a perspective view of the toy spinning top, showing my new design.

The essential features of my design reside in the full line portions shown and is characterized by the undulating monorail in combination with the toy spinning top all as shown.

The opposite side is substantially similar in appearance to that shown.

I claim:

The ornamental design for a toy spinning top, as shown and described.
